UNITED STATES PATENT OFFICE.

GUSTAF E. STROM, OF ST. PAUL, MINNESOTA, ASSIGNOR TO AMERICAN HOIST & DERRICK CO., OF ST. PAUL, MINNESOTA, A PARTNERSHIP.

BOTTOM-DUMP TRIPPING DEVICE.

1,302,876.

Specification of Letters Patent.

Patented May 6, 1919.

Application filed October 1, 1915. Serial No. 53,558.

To all whom it may concern:

Be it known that I, GUSTAF E. STROM, citizen of the United States, resident of St. Paul, county of Ramsey, State of Minnesota, have invented certain new and useful Improvements in Bottom-Dump Tripping Devices, of which the following is a specification.

The object of my invention is to provide a tripping device for the bottom dump of an excavating dipper of such construction that the trip line can be utilized for pulling the dipper backwardly toward the heel of the boom when the dipper arm is in a substantially vertical position, and when the arm is in a substantially horizontal position, the trip line will become effective to release the latch and dump the contents of the dipper.

Other objects of the invention will appear from the following detailed description.

The invention consists generally in various constructions and combinations, all as hereinafter described and particularly pointed out in the claims.

In the accompanying drawings forming part of this specification,

Figure 1 is an elevation of an excavating machine and boom, showing the application of my invention thereto,

Fig. 2 is a detail sectional view of the trip device by which the dumping of the dipper is controlled.

In the drawing, 2 represents an excavating machine, having a boom 3, a dipper 4, and a supporting arm 5. 6 represents the hinged bottom of the dipper, normally secured by a locking latch 7. This bottom is hinged at 8 in the ordinary way and when released will drop down to allow the contents of the dipper to be discharged. 9 is a casting, secured to the arm 5 by suitable means, such as bolts 10, provided with a recess 11 in which a swinging link 12 is pivoted at 13. This link has a socket 14 in one edge to receive a head 15 on a follower plate 16 that is mounted to move in a barrel 17 and is normally projected against the edge of the link by a helical spring 18. An adjusting screw 19 is provided for regulating the tension of this spring. A chain 20 is connected with the free end of the link 12

and extends to the latch 7 and a trip line 21 is also connected to said link and extends to some suitable operating means of the excavating machine. When the dipper is in the position substantially as shown in Fig. 1, a pull on the trip line will disengage the locking latch, release the bottom of the dipper and allow the contents to be dumped. Should the dipper arm be substantially vertical, a position it would normally assume by gravity when the lifting cable is slackened, the link 12 would then be substantially horizontal and an inward pull of the trip line would be exerted in a direction lengthwise of the link and cause the dipper to be drawn inwardly toward the excavator without tripping the latch of the bucket. In this way I am able to utilize a single line for the double purpose, acting in one position as a means for operating the dipper arm and in another for tripping the latch and dumping the contents of the bucket.

When the trip line is released after the movement of the link 12 and the compression of the spring 18, the tension of the spring will return the link to its normal position, allowing the locking latch to automatically return to its normal position and lock the bottom of the dipper when it is closed.

In various ways the details of construction herein shown and described may be modified without departing from the spirit of my invention.

I claim as my invention:

1. A device of the class described comprising a casting having means for attaching it to a dipper arm, a link pivoted at one end in said casting and having freedom of oscillation therein in a vertical plane, flexible means connecting said link with the latch to be tripped, a trip line also connected with said link for oscillating it, and a spring mounted to resist the movement of said link through the pull on said trip line.

2. A trip device for an excavating apparatus dipper comprising a casting having means for mounting it on a dipper arm and provided with a barrel and a compression spring therein, a link pivoted at one end within said casting and bearing on said spring, means connecting said link with the

latch to be tripped and a trip line connected with said link for swinging it to trip said latch against the tension of said spring.

3. A device of the class described comprising a support having means for securing it to a dipper arm, a link pivoted at one end within said support and free to oscillate therein, means connecting the other end

of said link with the latch to be tripped, a trip line connected with said link and a 10 spring device mounted to resist the movement of said link through the pull on said trip line.

In witness whereof, I have hereunto set my hand this 25th day of September, 1915. 15

GUSTAF E. STROM.
